UNITED STATES PATENT OFFICE.

GREGORY PENN, OF DALLAS, TEXAS.

GARMENT HANGER.

Application filed July 9, 1925. Serial No. 42,433.

This invention relates to new and useful improvements in garment hangers, and has for its principal object the provision of a hanger of this description particularly designed and constructed for use in installation in a delivery vehicle. The hanger, however, is adapted to be used very advantageously in clothes closets, wardrobes, clothing stores and wherever clothing is suspended.

Further objects of the invention are that the hanger is of comparatively few parts, may be economically constructed and is very strong and durable, being constructed entirely of steel, or other strong metal.

The advantages of the garment hanger and its form of construction and operation will be better understood by reference to the following description taken in connection with the accompanying drawings forming a part hereof and in which:

Figure 1 is a side elevational view of the invention illustrating the same embodied in a delivery vehicle.

Figure 2 is a detail-view of the operating end of the hanger.

Figure 3 is a detail view of the latching means.

Figures 4 and 5 are cross-sectional views on lines 4—4 and 5—5 respectively of Figure 1.

Figure 6 is a side view of the garment hanger illustrating its arrangement in a clothes closet, and

Figure 7 is a longitudinal sectional view of a support or base for the device where applied to a closet, wardrobe or similar place.

In carrying out the invention there is provided a metallic bar 1 preferably of square formation which has two bracket members 2—2, one at each end, shown clearly in Figure 4. These bracket members are provided with laterals 3—3 for the reception of screws 4—4 for attaching the bar 1 to the roof of a vehicle 1^a or other place. These brackets rigidly support the bar in position.

Depending from the operating end of bar 1, see Figure 2, is a small plate 4, held in place by a screw-bolt 5. The lower end of this plate is apertured, the purpose of which will be explained later.

Below the bar 1 is a member bent upon itself and forming two parallel bars 6 and 7, the upper one being cylindrical and the lower one of relatively flat formation and provided with spaced apertures 8—8. These

apertures are for the purpose of suspending wire members upon which a garment is placed, such as coats, suits, and the like.

By reference to Figures 1, 4 and 5 it will be observed that the lower bar 7 has formed thereon a member 9 and 10, and a roller bearing 11 placed thereon. The member 9 encloses the top portion of bar 1 and is rigidly secured to the two lower bars, the roller 11 adapted to ride upon the top of bar 1. The member 10, however, is disposed so as to entirely enclose the lower-most bar 7 and the roller 11 arranged to ride underneath the bar 1. In this manner the member comprising the two bars 6 and 7 may be slid backward and forward freely. The front end of the bar 6 is also passed through an opening in the plate 4 which acts as a support and guide.

The means for moving the device backward and forward is provided for by a handle A formed by the curved portion of the two rods 6 and 7 in conjunction with a catch lever 12—the handle and lever being grasped by the hand. This lever has a spring 13 encircling a pin 14 and is pivoted to a support 15 secured to rod 1. Compression of the spring permits the pin 14 to move through the support 15 and thus cause the lever 12 to be released from a small lug 16.

After this lug has passed the lever 12, the end of the latter frictionally engages the upper bar 6 and holds the movable member at any desired point.

The dotted lines in Figure 1 illustrate the position taken by the device when pulled outward from the vehicle, and in this connection it will be observed that the driver of the vehicle need not enter the same in removing or placing the garments on the device.

In Figures 6 and 7 is shown the manner of placing the hanger in a clothes closet. In this arrangement the bar 1 is screwed to a wood or other base 16 by a screw 17, aided by a brace bar 18. The base has apertures 19—19 for engagement with pegs or nails. The hanger is entirely within the closet between the wall 20 and door 21 and the garments 22 may be drawn out easily as shown by the dotted line position.

It should be understood that minor changes may be made in the construction of the device in keeping with the following claims:

1. In a garment hanger the combination of a main supporting rod, a member bent upon itself and forming two parallel verti-

2
cally spaced bars, the lower one of which is apertured to receive garment supports, means for adapting said bars to move backward and forward in alinement with said rod and a latch means mounted at one end of the rod for holding the bars in a locked position and frictionally engaging one of the bars during the movement of said member.

2. In a garment hanger the combination of
10 a main supporting rod and a looped member forming two spaced bars, an apertured plate attaching the looped member to one end of said rod, a plurality of plates rigidly securing said bars together, embracing said rod
15 and adapted to permit the bars comprising the looped member to travel in parallel relationship to said rod, and a handle and latch means for locking the looped member in position.

20 3. A garment hanger comprising a main supporting rod and two lower bars spaced

apart therefrom, the lower of said bars provided with apertures to receive members upon which the garments are hung, a plurality of plates rigidly secured to the bars and carrying roller bearings to permit the bars to ride in alinement with said rod, a lever pivoted to one end of said rod, a spring and a pin carried by said lever and a lug on one of said bars to form a stop for the lever to lock the lower bars against movement.

4. A garment hanger comprising a supporting rod, a hanger carrying bar slidable in parallel spaced relation to and mounted on said rod, and latch means arranged on one end of the supporting rod to hold the bar in closed position and frictionally engage said bar during movement of the latter.

In testimony whereof I have signed my name to this specification.

GREGORY PENN.
